US00D442628S

(12) **United States Design Patent**
Webb et al.

(10) Patent No.: **US D442,628 S**
(45) Date of Patent: **** May 22, 2001**

- (54) **CARD WITH AN ORNAMENTAL
RECTANGLE AND EXHIBITING AN
OPACITY GRADIENT**
- (75) Inventors: **Lisa Webb**, Darien, CT (US); **William
J. Faenza, Jr.**, Manassas, VA (US);
Ellen Lasch, NY; **Judy Vigiletti**,
Croton, both of NY (US)
- (73) Assignee: **American Express Travel Related
Services Company, Inc.**, New York,
NY (US)
- (**) Term: **14 Years**
- (21) Appl. No.: **29/110,196**
- (22) Filed: **Sep. 1, 1999**
- (51) LOC (7) Cl. **19-08**
- (52) U.S. Cl. **D19/10; D19/9**
- (58) Field of Search **D14/435, 436,
D14/437, 438, 479; D19/9, 10; 235/380-382.5,
441-443, 449, 454, 457, 469, 487-494;
283/72, 74, 75, 77, 78, 82-93, 107-114,
904**

(57) **CLAIM**

The ornamental design for the card with an ornamental rectangle and exhibiting an opacity gradient, as shown.

DESCRIPTION

FIG. 1 is a perspective view of a card with an ornamental rectangle and exhibiting an opacity gradient, showing my new design;

FIG. 2 is a front view of the card with an ornamental rectangle and exhibiting an opacity gradient of FIG. 1; FIG. 3 is a rear view of the card with an ornamental rectangle and exhibiting an opacity gradient of FIG. 1; FIG. 4 is a right side elevational view thereof; FIG. 5 is a left side elevational view thereof; FIG. 6 is a front elevational view thereof; and, FIG. 7 is a rear elevational view thereof.

The numerals and indicia depicted by means of broken lines in the drawing figures have been shown for illustrative purposes only and form no part of the claimed design.
